UNITED STATES PATENT OFFICE.

GEORGE W. CHRISTOPH, OF WAREHOUSEPOINT, CONNECTICUT.

EXHAUSTER.

1,401,583.

Specification of Letters Patent. Patented Dec. 27, 1921.

Application filed July 9, 1918. Serial No. 244,021.

To all whom it may concern:

Be it known that I, GEORGE W. CHRISTOPH, a citizen of the United States of America, residing at Warehousepoint, in the 5 county of Hartford and State of Connecticut, have invented certain new and useful Improvements in Exhausters, of which the following is a specification.

This invention relates to improvements in 10 exhausters of the general type disclosed in my prior Patent No. 1,074,606 issued October 7, 1913.

The exhauster of my prior patent is particularly adapted for transferring gases 15 laden with particles of solid matter, such as emery, coal dust, sawdust, shavings and the like, and is characterized by an arrangement such that contact of the solids with the blades of the rotor is avoided, or at least 20 reduced to a large extent. This advantageous result is obtained by a specially constructed casing wherein the passage, through which the gases and solids pass, is so disposed that a portion of the passage from 25 inlet to outlet lies out of the path of the rotor. The inlet portion of the passage is arranged to one side of the plane of the rotor and encircles the axis thereof helically so as to gradually extend into the plane of 30 the rotor.

The described passage is also arranged so as to communicate laterally throughout substantially its entire length with that portion 35 of the casing which houses the rotor. To a certain extent such lateral communication allows the gases to "jump" across into the path of the rotor and thus diminish the velocity of the gases which is relied upon to propel the solids through the passage. 40 Another difficulty which tends to diminish the efficiency of the exhauster is the opportunity afforded for the gases to not only "jump" across into the path of the rotor, but also to continuously travel with the 45 rotor in a circular path. Since centrifugal action is relied upon to separate the solids from the gases during their passage in a circular path, the diminution in the velocity of the gas at such points in the exhauster 50 where gravity opposes the action of centrifugal force on the solids, tends in certain cases to allow the solids to be carried by gravity out of their proper path. This invention is concerned among other things 55 with improvements designed to overcome the disadvantages mentioned.

The broad object of the invention is to provide an improved exhauster, of the general type described, which is characterized by improved efficiency and a more effective 60 separation of the solids from the gases, due to the provision of means preventing the gases from passing into the plane of the rotor until a predetermined point in their travel, and of means preventing the gases 65 from being carried continuously around with the rotor in a circular path and thereby diminishing the velocity of the gas and thus the effectiveness of the separation of gas and solids and the efficiency of the exhauster. 70

This object may be attained by the following structural arrangement. The rotor inclosing casing is provided with a free arcuate passage between its inner peripheral wall and the rotor and with a substantially 75 tangential outlet for such passage. In an end wall of the casing are separate inlets for gas and solids, which inlets lead respectively into and out of the path of the rotor. A main inlet duct, having an arcuate 80 portion with divided communication with both inlets, is arranged to receive gas laden with solids and such material, when carried in an arcuate path by reason of the revolving rotor, is separated into its constituents. 85 The separated solids, emerging from the outer peripheral portion of the duct, are deflected into the inlet for solids and preferably a hopper or chute is associated with the deflector and such inlet to facilitate this action. 90 The gas emerging from the duct, having been maintained up to this time at sufficient velocity to perform its desired function, passes directly to the other inlet and into the path of the rotor to be subsequently expelled 95 at high velocity from the outlet and to again act on the solid material and carry it through the outlet, while the material is held by centrifugal force in said passage and out of the path of the rotor. The said passage is provided with a suitable deflector adjacent the outlet to prevent the gas from traveling continuously around with the rotor. 100

Another object of the invention is to provide in an exhauster of the class described 105 regulating means for the inlet opening, through which solid material enters the rotor compartment, to the end that such opening may be varied in accordance with the character of the solid material being 110 handled.

According to this object, the exhauster is

arranged so that it may operate efficiently on varying classes of work by the adjustment which permits adaptation of the exhauster to each particular class of work to which it may be put. Thus, in practice, the percentage of solid material in the gases varies according to the nature of each particular case, and for example may be less when sawdust, shavings, and the like are handled than where emery and the like is the substance conveyed. By keeping the inlet opening restricted, so far as the nature of each particular case will admit, the efficiency of the exhauster and the effectiveness of the separation obtained, is improved.

A further object of the invention is to provide in an exhauster of the class described generally improved structure and a generally improved arrangement and disposition of parts.

Other objects and advantages will appear in the following description and in the appended claims.

The invention, in an embodiment at present preferred, is disclosed for illustrative purposes in the accompanying drawings, in which:

Figure 1 is a front elevational view of an exhauster embodying the invention;

Fig. 2 is a side elevational view thereof;

Fig. 3 is a cross-sectional view taken on the line 3-3 of Fig. 1;

Fig. 4 is a sectional elevational view taken on the line 4-4 of Fig. 2;

Fig. 5 is a fragmentary sectional elevation taken on the line 5-5 of Fig. 2;

Fig. 6 is a partial cross-sectional view taken on the line 6-6 of Fig. 5; and

Fig. 7 is a sectional elevational view taken on the line 7-7 of Fig. 2.

Referring to these drawings: the exhauster casing A, of generally cylindrical form, is divided by a central partition 10 (Fig. 3) into two substantially circular compartments 11 and 12. The two compartments communicate by way of a central circular opening 13 in the partition 10 and by another opening later to be described. Rotatably supported in suitable bearings fixed to the ends of casing A is a shaft 14, which may be driven by the pulley shown to rotate a fan or rotor 15 fixed to shaft 14 and disposed in compartment 12. The rotor 15 may be of any suitable type, but preferably is of the multi-blade type clearly shown in Fig. 7, wherein there are provided a multiplicity of relatively small and closely spaced vanes 16. It is to be noted that the rotor 15 is of such dimensions as to leave a substantial space between it and the inner peripheral wall of compartment 12 to afford a free annular passage 17 through which solid material may pass without coming into direct contact with vanes 16.

The compartment 11 has a horizontally

disposed inlet duct 18 which is also directed substantially tangentially to the circular opening 13 at the lowest point thereof. The upper wall of the inlet duct 18 is extended in a curved path concentric with the axis of rotor 15 to form a partition or baffle plate 19 which, as best shown in Fig. 4, extends through an arc of substantially 180 degrees forming a closed arcuate passage 20 as a continuation of the inlet duct 18. Starting substantially at the same angular position where the partition 19 terminates, is a helical deflector 22 which extends substantially to and terminates adjacent the upper wall of inlet pipe 18. As indicated in Figs. 3 and 4, the deflector, starting from the outer wall of compartment 11 and adjacent the terminus of partition 19, gradually curves laterally toward and finally terminates in the plane of the central partition 10. The deflector 22, as shown, is considerably less in width than the passage 20 since it is arranged, as will later appear in detail, to force merely the solids carried by the gas into the rotor compartment 12, the gas itself to a large extent passing through the large, free and unobstructed central opening 13 into the direct path of the rotor 15.

As best shown in Fig. 3, the deflector 22 is merely an arcuate plate suitably suspended from the peripheral wall of compartment 11 and suitably bent laterally, like a helix, toward the partition 10. An arcuate plate 23 extends in concentrical relation with the peripheral wall of compartment 11 from a point substantially midway of the deflector to its terminus at partition 10. This plate, in conjunction with the deflector 22, and the adjacent portions of partition 10 and the peripheral wall of the compartment 11, forms a closed hopper-like chute 24 (Figs. 3, 5 and 6). Such chute, as will best be seen in Fig. 5, is substantially vertically disposed and at its base communicates with the annular portion 17 of compartment 12 through an opening 25 (Figs. 6 and 7) formed in the partition 10. The opening 25 is regulable and may be varied by moving an arcuate plate 26 (Figs. 5 and 6) mounted in suitable guides in contiguous relation with partition 10 and capable of being swung to and adjustably held in various angular positions to restrict or enlarge the effective area of the inlet 25 by suitable means such for example, as indicated conventionally in Fig. 5.

Referring to Figs. 4 and 5, a baffle plate 27 is fitted about chute 24 and extends in downwardly inclined relation toward and tangentially to the circular opening 13 in partition 10. The plate 27 is provided as a means to insure that such solid matter, which for any reason, such as improper adjustment of the plate 26 for example, fails to lodge in chute 24, will be passed by gravity

through opening 13 into the rotor compartment 12 and be subsequently expelled.

- Referring now to Fig. 7; the rotor compartment 12, has an outlet pipe 28 which is disposed vertically and substantially tangentially to the annular passage 17 for the solid material. Adjacent the outlet 28, a deflector 29 is provided to substantially close off the passage 17 and prevent to a large extent the gases from following around with the rotor. The deflector also serves to deflect such solid material as is not expelled tangentially from the rotor in a straight line through outlet 28, although for the most part the solids are so expelled. The air, however, not being as susceptible to the action of centrifugal force, might to a large extent follow around with the rotor except for the deflector 29.
- 20 The operation of the exhauster will now be described. Assuming for example that air laden with solids is drawn into the inlet 18 by the suction created by the revolving rotor 15, the air continues into the arcuate passage 20 and there the solids are thrown by centrifugal force toward the outer peripheral portion of the passage. Thus the solids, as they emerge from the curved chute-like passage 20, are so positioned as to be engaged by the helical deflector 22. Obviously, as the solids pass across the upper peripheral portion of compartment 11, they are acted upon by gravity in such a way that they tend to leave the deflector 22 in a radial direction and, to prevent such misdirection of the solids under the force of gravity, the plate 19 is continued for a substantial distance around the periphery of the opening 13 so that the velocity of the air is maintained undiminished until it can be assured that the solids will be carried in the chosen path along the deflector 22 and into the hopper-like chute 24. As soon as this result has been accomplished, it is desirable to provide a free and relatively large inlet for the passage of the air into the path of the rotor 15 and this is accomplished by the large circular inlet opening 13, of a diameter substantially equal to that of the rotor 15 at the base of the vanes 16. The solids, once lodging in chute 24, travel toward the opening 25 and are aided in such travel by gravity action. The solids enter compartment 12 through the regulable opening 25 and into the annular portion 17 and thus entirely out of the path of the rotor. Due to the reflector 29, the air, entering through opening 13 into compartment 12, is prevented to a large extent from traveling around with the rotor and is caused to travel at high speed out of the compartment 12 through the outlet. Thus, the solids delivered into the passage 17 are still acted upon by centrifugal force and thereby thrown toward the periphery of the casing during their upward

and outward travel in passage 17. The solids, being acted upon by centrifugal force, tend to move in a straight line tangential to the passage 17 so that, as soon as permitted by the peripheral wall of the passage, they 70 pass in a straight line through the outlet 28.

An important feature in an exhauster of the special type described consists in the arrangement for regulating the opening 25 through which the solid material enters the 75 rotor compartment. By restricting the opening 25 so far as possible, considering the nature of each particular class of work, the efficiency of the exhauster and the effectiveness of the separation obtained, may be 80 greatly improved. The desired object, and the ultimate goal aimed at, is to close off opening 25 to such an extent that it is just sufficient to permit the passage of the solids only and, while such object probably cannot 85 be exactly obtained in practice, it can nevertheless be approached and the regulation of the opening 25 is the means for at least closely approaching the desired theoretical conditions. 90

Thus, I have provided an improved exhauster for transferring gases laden with solids without allowing the solids to directly contact with the rotor, or at least to any great extent. The improved exhauster is 95 characterized by regulating means to adapt the exhauster to the varying conditions of the work to which it may be put with the object of securing maximum efficiency with each class of work. The exhauster is also 100 characterized by improvements which permit separation of solids from gases laden therewith and permit such separation with increased effectiveness.

The invention has been disclosed in one 105 embodiment for illustrative purposes, but the scope of the invention is defined by the appended claims rather than by the foregoing description.

What I claim is,—

1. An exhauster, comprising, a casing provided with a rotor compartment, a rotor so located therein as to leave an arcuate passage between the rotor and the peripheral wall of said compartment, an outlet provided in the casing for said passage, said casing being provided with an inlet duct partially encircling the axis of the rotor in concentrical relation therewith and communicating at one end with the rotor compartment at points both into and out of the path of the rotor, the other end of said duct adapted to receive gases laden with solids all of which are forced to traverse a curved path before entering the rotor compartment, whereby the heavier particles may be separated from the lighter by centrifugal force and the former delivered into the compartment out of the path of the rotor. 115

2. An exhauster comprising, a rotor, a cas- 120

ing inclosing the rotor leaving a substantially annular space between it and the rotor and provided with an outlet, a closed duct curved throughout a portion of its extent and partially surrounding the axis of the rotor into one end of which gases laden with solids are drawn by the rotor the gases and solids being separated therein by centrifugal force, and separate inlet openings 10 provided in the casing leading into and out of the path of the rotor and both communicating with the other end of said duct, whereby the separated constituents are separately delivered.

15 3. In an exhauster, a rotor, a casing inclosing the rotor and having an arcuate passage between it and the rotor including a peripheral and substantially tangential outlet for the passage, a duct curved about the axis 20 of the rotor and through which gases laden with solids may be drawn by the rotor and in which the solids may be separated from the gases by centrifugal force, an inlet in the casing communicating with the inner peripheral portion of said duct to permit the gases therein to enter into the path of the rotor, and a second inlet in the casing communicating between the outer peripheral portion of the duct and said arcuate passage 25 whereby the solids may be separately delivered into the casing and out of the path 30 of the rotor.

4. In an exhauster, a rotor, an inclosing casing therefor having an arcuate passage 35 between the rotor and casing and a substantially tangential outlet from said passage, said casing having in an end face thereof an inlet opening into the path of the rotor and a second inlet opening into said 40 passage and out of the path of the rotor, a hopper associated with the second inlet and adapted to receive material to be passed therethrough, and a duct having an arcuate portion communicating with both the first 45 inlet and said hopper and into which portion gas laden with solids may be drawn by the rotor, all constructed and arranged so that the solids may be separated from the gas and separately delivered into the hopper and to the casing through the second inlet.

5. In an exhauster, a rotor, an inclosing casing therefor having an arcuate passage 55 between the rotor and casing and a substantially tangential outlet from said passage, said casing having in an end face thereof an inlet opening into the path of the rotor, and a second inlet opening into said passage and out of the path of the rotor, a hopper to receive material to be passed through the 60 second inlet, means to vary the effective opening of the second inlet, and a duct having an arcuate portion communicating with both said inlets and into which portion gas laden with solids may be drawn by the rotor, 65 all constructed and arranged so that the

solids may be separated from the gas and separately delivered into the hopper and to the casing through the second inlet.

6. In an exhauster, a rotor, a casing inclosing the rotor and having an arcuate passage between it and the casing including a peripheral and substantially tangential outlet for the passage, a duct having an arcuate portion through which gases laden with solids may be drawn by the rotor and in which the solids may be separated from the gases by centrifugal force, an inlet in the casing communicating with the inner peripheral portion of said duct to permit the gases therein to enter into the path of the 70 rotor, and a second inlet in the casing communicating between the outer peripheral portion of the duct and said arcuate passage 75 whereby the solids may be delivered into the casing and out of the path of the 80 rotor, and regulating means to vary the effective area of the second inlet.

7. In an exhauster, a rotor, an inclosing casing therefor having an arcuate passage between the rotor and casing and provided with a substantially tangential outlet from said passage, said casing being provided in one end face thereof with an inlet opening into the path of said rotor and a second inlet opening into said passage and out of the 90 path of the rotor, a hopper associated with the second inlet and adapted to receive material to be passed therethrough, said casing provided with a duct having an arcuate portion 95 communicating with the first-named inlet and said hopper and into which portion gas laden with solids is adapted to be drawn by the rotor, said duct being arranged so that the solids are carried by centrifugal force to the outer periphery thereof, and means connecting the outer peripheral portion of the duct to the hopper whereby the solids are forced laterally into the mouth of the hopper.

8. In an exhauster, a rotor, an inclosing 110 casing therefor having an arcuate passage between its periphery and the rotor and provided with a substantially tangential outlet for such passage and an inlet in one end wall thereof, and an arcuate duct partially 115 encircling the axis of the rotor, but out of the plane thereof, and terminating adjacent said inlet, said casing being provided with a second inlet formed in one end wall thereof and opening into the path of the rotor, 120 and means connecting the duct at a point closely adjacent to its uppermost part with said second inlet.

9. In an exhauster, a casing separated by a partition wall into two generally cylindrical compartments arranged side by side and connected by a central opening formed in the partition wall, a rotor in one compartment so positioned as to leave a free arcuate passage between the rotor and the pe- 125 130

ripheral wall of the compartment, said casing being provided with a tangentially disposed outlet communicating with said passage, partitioning means partially encompassing said central opening and affording a curved inlet duct into which gas laden with solids may be drawn and in which the solids are adapted to be separated from the gas by centrifugal force, said partition wall being provided with an opening leading to said passage, and a deflector extending from a point adjacent the end of said duct to the last-named opening for deflecting the separated solids laterally into said last-named opening.

10. An exhauster comprising a rotor, a casing inclosing the rotor and providing an

arcuate passage between it and the rotor, said casing being provided with an outlet communicating with said passage and extending substantially tangential relative thereto and an inlet opening into said passage, said casing being also provided with a second inlet opening into the path of the rotor and a duct into which gases laden with solids are adapted to be introduced, said duct being curved throughout a portion of its length about the axis of the rotor whereby the solids and gases are adapted to be separated by centrifugal force, said duct being in communication with both of said inlets to deliver the separated solids to said first inlet and the gases to said second inlet.

GEORGE W. CHRISTOPH.
